UNITED STATES PATENT OFFICE

OSCAR MYER, OF YOUNGSTOWN, OHIO

DESIGN FOR A SET OF PUZZLE NUMERALS

Application filed July 3, 1930. Serial No. 36,259. Term of patent 7 years.

To all whom it may concern:

Be it known that OSCAR MYER, a citizen of the United States of America, residing at Youngstown, in the county of Mahoning and State of Ohio, has invented a new, original, and ornamental Design for a Set of Puzzle Numerals, of which the following is a specification, reference being had to the accompanying drawing, forming part thereof.

The figures show plan views of a set of

puzzle numerals, showing my new design. The numerals are about $\frac{1}{4}$ of an inch in thickness and all of the faces are plain except the one shown.

I claim:

The ornamental design for a set of puzzle numerals, as shown and described.

In testimony whereof I affix my signature.

OSCAR MYER.
